 By Attorney.

UNITED STATES PATENT OFFICE.

TERTULLUS S. DIBLIN, OF TRENTON, NEW JERSEY.

DESIGN FOR A FLOOR-MAT.

SPECIFICATION forming part of Design No. 25,247, dated March 10, 1896.

Application filed January 6, 1896. Serial No. 574,552. Term of patent 7 years.

To all whom it may concern:

Be it known that I, TERTULLUS S. DIBLIN, a citizen of the United States, residing at Trenton, in the county of Mercer and State of New Jersey, have invented and produced a new and original Design for a Floor-Mat; and I do hereby declare the following to be a full, clear, and exact description of the same, reference being had to the accompanying drawing, forming a part thereof.

The figure is a plan view of a mat embodying my design.

The same reference-letters denote the same parts in the drawing.

The leading feature of my design consists of a mat having a field-space which opens between the end sections of the mat and is partially inclosed by said sections and the middle mat-section.

The mat is composed of a series of ribs B, extending from the outside border, C, to the inside border, D, and similar ribs E, which in-

tersect the ribs B, extend from one to the other of the ends F, and form squares a, having diagonal ribs b. The outside border, C, is formed of a series of S-shaped figures and the inside border is composed of a series of diamond-shaped figures. The middle section, or portion of the mat midway between the ends F, is curved or semicircular, and said ends are continued straight and parallel with each other from the semicircular section, leaving a space G in the field of the mat partially inclosed by the said middle section and the end sections.

35

What I claim is—

The design for a floor-mat herein shown and described.

In testimony whereof I affix my signature in presence of two witnesses.

TERTULLUS S. DIBLIN.
